 Ohio, a corporation of Ohio

Application May 27, 1932, Serial No. 613,901

11 Claims. (Cl. 51—105)

This invention relates to improvements in machine tools and especially to improvements in compensating mechanism for maintaining proper relation between the tool and work.

5 An object of the invention is the provision of improved control means associated with the tool feed mechanism to insure successive work pieces being reduced to the same size.

Another object of the invention is the provision 10 of a grinding machine including a grinding wheel and truing mechanism therefor and improved means for compensating or varying the relationship between the grinding wheel and the work in accordance with normal reductions in diameter 15 of the grinding wheel due to normal break down and truing thereof.

A further object of the invention is the provision of improved means for maintaining the desired relationship between the grinding wheel and 20 a work piece whereby the work pieces are reduced to the same size within prescribed narrow limits of tolerance.

Other objects and advantages of the present 25 invention should be readily apparent by reference to the following specification considered in conjunction with the accompanying drawings, forming a part thereof, and it is to be understood that any modifications may be made in the exact structural details there shown and described within 30 the scope of the appended claims without exceeding or departing from the spirit of the invention.

In the drawings:

Figure 1 is a front elevation of a grinding machine embodying the improvements of this invention.

35 Figure 2 is a top plan view of the machine shown in Figure 1.

Figure 3 is a sectional view through a self-contained wheel head associated with the machine and as seen particularly from line 3—3 on Figure 2 but with the swivel bracket member 87 swung outward into a position such that the hand wheel 92 overlies the drive motor 47.

Figure 4 is a sectional view taken on line 4—4 of Figure 3.

Figure 5 is a sectional view taken on line 5—5 of Figure 3.

Figure 6 is an elevational view of a cam associated with the self-contained wheel head for controlling the cycle through which the wheel head passes.

Figure 7 is a sectional view through the truing mechanism taken substantially on line 7—7 of Figure 2.

55 Figure 8 is a sectional view through the truing

actuating mechanism taken on line 8—8 of Figure 7.

Figure 9 is a sectional view through the head adjusting mechanism taken on line 9—9 of Figure 3.

Figure 10 is an elevational view of a valve and its control for actuating the piston shown in Figure 9.

Figure 11 is a transverse sectional view through a manually operated valve controlling the actuation 10 of the truing mechanism transversely of the grinding wheel.

Figure 12 is a diagrammatic view illustrating the electrical and hydraulic circuits involved in this invention.

Throughout the several views of the drawings similar reference characters are employed to denote the same or similar parts.

It has been proposed to produce a machine comprising a plurality of self-contained tool units 20 which are automatically and independently actuated for independent operation on spaced portions of a given work piece. These self-contained units are relatively massive and cover a considerable area so that certain of the controls, particularly the truing mechanism, are remote from the operator rendering it difficult to properly actuate said mechanism.

Furthermore, the operation of the truing mechanism in the past has resulted in the work being produced outside of the limits 25 of tolerance prescribed for the work, so that the operator must bring his machine within size by the cut and try method, which consumed a considerable portion of time. By this invention, the

machine after being once brought into adjustment for producing work pieces within the prescribed tolerance limits is at all times automatically maintained in proper adjustment.

While the invention is illustrated in the drawings and will be particularly described as respects a multiple production machine, it is to be understood 40 that the invention has equal application to single unit machines.

The machine illustrated in the drawings comprises a relatively low rectangular bed or bed plate 15 having rising therefrom centrally thereof a rib 16 providing on its upper surface a dove-tailed guide 17.

Associated with the guide 17 at one end is the self-contained head stock 18 and at the other end the self-contained tail stock 19, respectively providing suitable work support-

ing centers for the work, which is mounted between them. Arranged on the bed 15 on both sides of the central rib 16 are the self-contained tool heads, 20, 21, 22 and 23, which are substan-

tially identical in construction wherefor the single head will be described in detail later.

The bed 15, see Figure 1, has rising from the opposite ends thereof posts or columns 24 and 25 supporting at their upper ends a rail 26, which overlies the rib 16. Secured to the rail 26 and depending therefrom is a frame 27 forming a magazine 28 for unfinished work pieces and supporting a discharge chute 29 for the reception of finished work pieces. Depending from the rail 26 adjacent the magazine and discharge chute is a slide or guide 30 for a work support or carrier 31 adapted to receive unfinished work pieces from the magazine 28 and position same between the supporting centers of the head and tail stocks. The carrier 31 is further adapted to carry finished work pieces from between the head and tail stocks to the discharge chute 29. The carrier 31 is hydraulically actuated for the control of which the rail 26 supports the proper valve controlling members 32. The foregoing form no particular part of the invention of this application except in combination, as will later appear.

Each of the wheelheads consists of a base 33 adapted to be secured in any desirable position on the bed 15 having formed on its upper surface a dove-tailed guide 34 received in a similarly shaped guideway 35 formed in a slide 36. The slide 36 is provided at its forward end with trunnion bearings 37 in which is secured a trunnion or pivot shaft 38 having its opposite ends projecting from the trunnion bearings 37. The projecting ends of the trunnion 38 are loosely received in arms or lugs 39 and 40 depending from the wheel carriage 41.

The wheel carriage 41 supports suitable bearings or journals 42 in which is rotatably journaled a spindle 43 to the forward end of which is secured the grinding wheel in any suitable or desirable manner. The rear end of the spindle 43 is provided with a chain sprocket or gear 44 about which extends the driving chain 45 which is in turn journaled about a sprocket secured to the end of motor shaft 46. The motor shaft 46 is associated with a prime mover or an electrical motor 47 mounted upon the upper surface of the carriage 41 provided for that purpose.

The carriage 41 is adapted to be oscillated about the axis of the trunnion 38 toward and from the work to effect a reduction in the size of the work to the desired size, which is within certain definite tolerances, variably specified as several ten-thousandths of an inch or one or two thousandths of an inch. In order to oscillate the carriage 41, it has secured to its under surface a bracket 48 having rotatably journaled therein anti-friction roller 49 contacting with the surface 50 of a cam 51 secured to the shaft 52 and rotatably journaled in the carriage 36. The cam 51 is shown in Figure 6 and comprises a low point 53 which when in contact with the roller 49 permits complete retraction of the grinding wheel from the work. The periphery of the cam is provided adjacent the low point 53 with a rapid incline 54 which extends to the point 55 for rapidly advancing the carriage toward the work to a position where the grinding wheel just touches the work. From the point 55 to the point 56 the periphery of the cam rises gradually to effect the actual stock removal or grinding on the work from which point to the point 57 the periphery is concentric allowing a dwell in the relative movement of the work and grinding wheel and permitting the sparking out of the grinding wheel. The periphery of the cam

sharply falls away or declines from the high point 57 to the low point 53 for rapidly retracting the grinding wheel from the work after it has been reduced to the desired size and finish. From this it will be seen that the grinding wheel rapidly approaches the work, reduces same to size, dwells to properly clean up and finish the work, and then rapidly withdraws from the work.

In order to rotate the cam 51 the slide 36 supports beneath the carriage 41 a prime mover or electric motor 58 having secured to its shaft a pinion 59 meshing with a gear 60 on one end of a shaft 61 journaled in suitable bearings provided by the slide 36 and the change gear housing 62. The shaft 61 carries, in addition, a gear 63 which drives through a suitable transmission or gear train to the change gear 64 on one end of a shaft 65 and driving through gears 66 to a worm shaft 67. The worm shaft 67 is journaled in bearings provided by the slide 36 and change gear housing 62 and has integral therewith a worm 68 meshing with a worm wheel 69 on the cam shaft 52. From this it will be seen that the grinding wheel may be oscillated through the cycle above described at different speeds by changing the gears 64 and that the grinding wheel is actuated toward and from the work.

In order to vary the position of the grinding wheel relative to the base plate 33 the said base plate is provided at its forward end with an upstanding lug 70 having a threaded perforation therein receiving the threaded end of a screw 71 rotatably journaled in a lug 72 depending from the lower surface of the slide 36. The rear end of the screw is reduced as at 73 and is journaled in a socket 74 formed in the slide 36. Between the lug 72 and socket 74 the carriage is relieved to provide a passageway in which is disposed a spiral gear 75 secured to the reduced end 73 of the screw. Meshing with the spiral gear 75 is a complementary spiral gear or worm secured to or formed integral with a vertically extending shaft 76 which is rotatably mounted in a sleeve 77 carried by the slide 36. The sleeve 77 is enclosed within a guard sleeve 78 which is also carried by the slide 36 and passes upwardly through an enlarged opening 79 formed in the upper surface of the carriage 41. By this construction the carriage 41 may be oscillated relative to the slide 36 without interference from the guard sleeve 78 or the parts enclosed thereby. In order to prevent foreign materials from entering within the carriage 41, the sleeve 78 carries at a point above the opening 79 a cap or cover 80 normally sealing the said opening 79.

The vertical shaft 76 extending through the sleeve 77 is journaled on anti-friction bearings 81 mounted on the upper surface of the sleeve 77 and the bearing 81 contacts on its other surface with a collar 82. At the upper end of the shaft 76 beyond the collar 82 it is provided with a reduced portion 83 to which is keyed or otherwise secured a worm wheel 84. The worm wheel 84 is secured to the reduced portion 83 of the shaft by means of a nut 85 threaded to the extreme end of said shaft for clamping the worm wheel between itself and the shoulder at the end of the reduced portion 83. The worm wheel 84 has meshing with it a worm which is secured to or formed integral with a shaft 86 journaled at opposite ends in a swivel housing 87. The swivel housing 87 has at its one end a split collar 88 which encircles the upper reduced end of the guard sleeve 78. The collar 88 is concentric with

the axis of the guard sleeve 78 and the vertical shaft 76 so that by loosening the clamp the swivel housing 87 may be oscillated about the axis of the shaft 76 to dispose the outer end of the shaft 86 at any point as respects the bed of the machine. This is illustrated in Figure 2 where it will be seen that the ends of the said shafts terminate adjacent the portion 89 of the bed plate 15 intermediate the wheel heads 22 and 23 which constitutes the operator's station.

The outer end of the swivel housing 87 terminates in a collar 90 in which is journaled the end of the shaft 86 and to which is secured the control mechanism indicated generally by the numeral 91. The shaft 86 is reduced in order to pass through the unit 91 and has secured to it exteriorly of said unit a hand wheel 92 whereby the shaft 86 is rotated for rotating the shaft 76 and through the spiral gear 75 the screw 71, thereby adjusting the slide 36 and parts carried thereby relative to the base 33.

The control unit 91 consists of a ratchet 93, see Figures 3 and 9, keyed or otherwise secured to the reduced end 94 of the shaft 86. This ratchet is enclosed within a cavity 95 formed in a housing 96 that forms the control unit 91. Secured to the housing and interiorly thereof is a plate 97 having projecting therefrom a bearing sleeve 98 which encircles the reduced end 94 of the shaft. Loosely journaled on the collar or sleeve 98 is a segmental gear 99 having the teeth 100 thereof meshing with a rack 101 formed on or secured to the upper surface of a double acting piston 102. The piston 102 is contained within a cylinder 103 formed in the housing 96. The cylinder 103 is closed at opposite ends by heads 104 and 105 extending respectively from which are the screws 106 and 107 acting as stops or limits for the travel of the piston at each end of its movement. Pivoted as at 108 to the segmental gear 99 is a pawl 109 having its nose 110 adapted to engage with the teeth of the ratchet 93. The other end of the pawl 109 engages with a spring 111 extending from a spring carrier 112 projecting from the segmental gear 99. Passing through the upper wall of the housing 96 into the chamber 95 is a thumb or lock out screw 113 adapted to engage with the tail of the pawl 109 for disengaging the nose thereof from the ratchet teeth 93. The lock screw 113 has associated with it a lock nut 114 for locking it in its adjusted positions.

When the piston 102 is at the left hand limit of its movement, as seen in Figure 9, the lock out screw 113 engages with the end of the pawl 109 for holding the same disengaged from the ratchet 93 at which time the slide and carriage may be actuated through the hand wheel 92. It is the purpose of the ratchet and pawl mechanism, as will later appear, to automatically and periodically actuate same for periodically advancing the parts controlled thereby to maintain the work at all times within certain prescribed limits of tolerance. The piston 102 is adapted to be actuated relative to the cylinder by means of hydraulic pressure, which will be later described.

Each of the grinding wheels associated with the heads 20 to 23, inclusive, is adapted to be trued by mechanism individual to the respective heads but of similar construction wherefor it is believed that a description of one of them will suffice for all.

Accordingly, as seen in Figures 7 and 8, the wheel carriage 41 has secured to it the bracket 115 to which is secured a block 116 by means of bolts or the like 117. The block 116 has formed

therein a cylinder 118 in which is mounted a piston 119. The cylinder is closed at opposite ends by the heads 120 and 121 which limit the extent of travel of the piston relative to the cylinder. Secured to the piston and projecting therefrom is a piston rod 122 which passes through the head 121 and has secured to its outer end the depending lug 123 of a slide 124. The slide 124 is provided with a dove-tailed guide-way 125 receiving a correspondingly shaped tongue 126 formed on the upper surface of the block 116. The piston 119 is adapted to be actuated by hydraulic pressure introduced alternately to the opposite ends of the cylinder.

The slide 124 has formed integral therewith or secured thereto a sleeve bearing or barrel 127 in which is disposed a bar 128 adapted to be axially shifted relative thereto. The bar 128 has secured to its upper end as by cap screws 129 a nut 130 in threaded engagement with a screw 131. The inner end of the bar 128 has secured therein a diamond holder 132 for the diamond 133 which is adapted to operate upon the periphery of the grinding wheel.

The barrel 127 terminates in an enlarged head 134 forming interiorly thereof a chamber 135. Secured to the base of the chamber 135 interiorly thereof is a plate member 136 having projecting from it a bearing boss 137. Contacting with the under surface of the plate 136 is a shoulder 138 of the screw 131 which limits the axial movement of said screw in one direction. Keyed or otherwise secured to the reduced portion 139 of the screw and abutting the end of the plate bearing 137 is a ratchet 140 being secured against movement relative to the screw by means of a nut 141. The nut 141 co-operates with the shoulder 138 to secure the screw 131 against axial movement in either direction relative to the barrel 127. Secured to the head 134 of the barrel 127 is a cover plate 142 through which the screw 131 projects to receive the hand wheel 143 for manual rotation of the screw and initial setting of the parts.

Loosely journaled on the plate bearing 137 is a segmental gear 144 having its teeth 145 in mesh with a rack plunger 146 axially shiftable relative to a cylindrical housing 147 formed integral with the barrel head 134 at a point below the segmental gear 144. A pin and slot connection 148 limits the axial adjustment of the rack plunger 146 relative to its housing 147. Pivoted as at 149 to the segmental gear 144 for movement therewith is a pawl 150 having a nose 151 adapted to engage the teeth of the ratchet 140. Abutting the end of the pawl 150 is a spring 152 carried by the spring carrier 153 projecting from the side of the segmental gear 144. Extending through the barrel head 134 is a lock out screw 154 adapted to engage with the tail of the pawl 150 for raising the nose 151 out of engagement with the ratchet teeth when the segmental gear 144 is at one end of its rotary movement. With the parts in this position, the screw 131 may be rotated manually by the hand wheel 143.

As was mentioned above and as will be seen from Figure 2, in order to actuate the diamond relatively to the wheel it was necessary, in the past, for the operator to leave his station 89 and proceed to the rear of the machine for there independently and manually actuating the diamond mechanisms, thereby consuming considerable valuable time. To overcome this difficulty, the rail 26 has mounted thereon within convenient reach of the operator's station 89 a plurality of

valves, each identical in construction and respectively operated by hand levers 155, 156, 157 and 158. One of the valves is shown in detail in Figure 11 and consists of a body portion 159 in 5 which is mounted a rotary valve plug 160 having grooves cut therethrough at points diametrically opposed to one another to form the passages 161 and 162. The valve handle is secured to the plug 160 for oscillating same for at one time connecting the port 163 formed in one side of the body 159 with the port 164 as by way of the passage 161 and at the same time connecting the port 165 with the port 166 as by way of the passage 162. Oscillation of the valve plug 160 in a 10 counterclockwise direction will connect the port 163 with the port 166 by way of the passage 161 while the passage 162 connects the ports 164 and 165.

By reference to Figure 12, it will be noted that 20 the port 163 is connected by a conduit or pipe 167 with the discharge side of a pump 168 adapted to draw an hydraulic medium such as oil from a tank or sump 169 through a suction pipe 170. The port 164 is connected by means of the pipe or conduit 171 with one end of the truing tool traversing cylinder 118. The other end of this cylinder is connected by means of the pipe or conduit 172 with the port 166 while the remaining port 165 is connected by a discharge pipe or conduit 173 with the tank or sump 169. As shown 25 in Figure 12, the valve plug 160 is in the same position as that illustrated in Figure 11, thereby connecting pipes 167 and 171 for directing the pressure against the right hand end of the piston 119 and actuating the slide 124 to the right as seen in Figure 12. This exhausts the hydraulic medium ahead of the piston 119 through the pipes 172 and 173 to the tank 169.

The block 116 has secured to its right hand 40 end, as seen in Figure 8, a bracket 174 which has extending upwardly therefrom an arm 175 carrying an adjustable screw 176 for engagement with the end of the rack plunger 146 as the slide 124 reaches its right hand end of travel, 45 as seen in Figure 8. The arm 175 is further provided with a momentary switch 177 having projecting therefrom the switch actuator 178 mounted in the path of travel of an adjustable abutment 179 conveniently taking the form of 50 a screw or bolt threaded into a lug 180 depending from the lower surface of the plunger housing 147. The block 116 has secured to its side portion and projecting upwardly therefrom an arm 181 in which is mounted an adjustable abutment screw 182 for engagement with the other end 55 of the rack plunger 146. The plunger 146 is utilized for setting the segmental gear 144 relative to the ratchet 140 preparatory to the next infeed of the diamond carrier 132 which is accomplished at the other end of the stroke of the 60 slide 124 namely by the abutment 182.

As was noted above, in the past after the wheels 65 had been trued the relation of their operative faces as respects the axis of the work was destroyed so that it was necessary for the operator to again reset the parts by the cut and try method. This again consumed a considerable portion of valuable grinding time during the hand 70 measurement of the parts. Since the greatest variance between the wheel axis and the work axis takes place at the time that the wheels are trued, there has been provided a mechanism compensating for the amount of stock or material removed from the wheel after each truing 75 thereof. For this reason, the infeed shaft 86 is

provided with the mechanism 91 actuated by the piston 102. As shown in Figure 12, the cylinder 103 containing the piston 102 has its left hand end connected by means of the pipe or conduit 183 with a port 184, see Figure 10, formed in a valve casing 185 mounted on the carriage 41 of each head. The valve casing 185 encloses a rotary plug type valve 186 having extending therethrough three passages, 187, 188 and 189. Passages 187 and 189 are formed by providing slots 10 at diametrically opposite points in the valve plug, while the passage 188 is formed through same and between the passages 187 and 189. As shown structurally in Figure 10, and diagrammatically in Figure 12, the passage 187 is connecting the port 184 with a port 190 which has extending from it branch discharge or exhaust conduit 191. The other end of the cylinder 103 has one end of a pipe 192 connected thereto which pipe terminates at port 193 in the valve casing 185 and is connected by means of the central passageway with a port 194 also formed in the valve casing. The port 194 is connected by means of a pipe or conduit 195 with the pressure line 167 for conveying pressure to the valve 20 casing 185. The casing 185 is provided with an additional port 196 connected by the pipe or conduit 197 with the pipe or conduit 191 which is in turn connected to the return or exhaust conduit 173. Oscillation of the valve plug 186 25 in a counterclockwise direction, as seen in Figures 10 and 12, will connect the central passage 188 with the port 184 and thereby direct the medium to the right hand end of the cylinder 103 instead of to the left hand end thereof as is now 30 illustrated in Figure 12. At this time the port 193 would be connected with the port 196 for directing the exhaust medium through the line 197 instead of the line 191 as at present shown 35 in Figure 12.

The valve plug 186 has secured to it an arm 198 in which is formed an elongated perforation 199 receiving a pin 200 extending from the upper end of link 201. The other end of the link 201 is pivoted at 202 to the core 203 of a solenoid 45 204. The solenoid 204 is adapted to be electrically energized for shifting the valve 186 at the time the momentary switch 177 is closed.

As shown in Figure 12, one terminal of the switch 177 is connected by a wire 205 to the main 50 positive lead 206, while the other terminal is connected by a wire 207 to a time relay switch 208 and through a wire 209 with the main negative lead 210. From this it will be seen that closing of the switch 177 energizes the time relay 55 208 for closing the switch 211 to which is connected one end of the wire 209. The other terminal of the switch 211 is connected by a wire 212 with one end of the solenoid 204. The other 60 side of this solenoid is connected by means of a wire 213 with the positive lead 206.

To retract the solenoid core 203 after the current has been cut off therefrom, there is provided a spring 214 having one end connected to the pivot pin 200 of the link 201, while the other end is connected at 215 to a fixed part of the machine.

The operation of the device is as follows: A supply of work pieces is placed in the magazine 28 being normally held from discharge therefrom until the carrier 31 is in position to receive them. The carrier is then elevated by actuation of the valve control unit 32 to a position to receive the work whereupon it is lowered to position the 75

work in alignment with the head and tail stocks, which support and rotate same.

The infeed motors 58 are then started for rotating the cam 51 which feeds the grinding 5 wheels toward the work and retracts same therefrom. Previous to the operation of the motor 58, the slide 36 and parts carried thereby were adjusted relative to the base 33 to insure when the cam 51 reaches its high point 57 the work will 10 be reduced to the desired size, which will be near the low limit of tolerance. This adjustment of the carriage took place by means of the hand wheel 92 rotating the shaft 85 through the worm and worm wheel 84 and shaft 76 for rotating the 15 adjusting screw 71.

At the conclusion of the grinding operation the valve 32 is again actuated for elevating the work to the discharge chute 29 which receives said finished work piece whereupon a new unfinished 20 work piece is released from the magazine 28 and again lowered to position for grinding. This operation continues, the workman checking the sizes of the several portions of the work previously ground during the grinding of the work 25 piece now in the machine. If it is found that one of the diameters is nearing the upper limit of the tolerance size, he selects the valve handle 155, 156, 157 or 158 controlling the dressing or 30 truing mechanism for the desired wheel head 20, 21, 22 or 23, which is not reducing its work piece to the desired size. This operation of the valve handle, of course, takes place while the wheels are in a retracted position and with the work carrier elevated. The operation of the desired handle 35 shifts the valve plug 160 from the position shown in dotted lines in Figure 12 to the position shown in full lines therein. This connects the hydraulic medium with the left hand side of the piston 119 for actuating the slide 124 to the 40 right causing the diamond 133 to traverse past the wheel. In the event the wheel had worn below the point at which the diamond would engage to remove or trim its operative face, nothing would happen until the truing slide reaches 45 its right hand limit of movement. At this time, the rack plunger 146 engages with the stop 176 which, as noted above, resets the segmental gear 144 for the next infeed movement of the diamond. At the same time, the bumper 179 carried 50 by the truing slide engages the switch actuator 178 for closing the electrical switch 177. This completes the electrical circuit including wires 205, 207, time relay 208 and wire 209 for closing the switch 211. The closing of the switch 211 55 completes the electrical circuit through wires 209 and 212, solenoid 204 and wire 213 for energizing said solenoid 204 and actuating the core 203 which will oscillate the valve 186 in a counter-clockwise direction. The movement of the valve 60 by the solenoid 204 connects the hydraulic medium with the left hand end of the piston 102, as seen in Figures 12 and 9, for actuating the piston in the direction for causing a feeding movement to the ratchet 93 and minutely rotating the carriage 65 infeed screw 71. The movement of the carriage 71 toward the work is of an amount equal to the amount removed from the operative face of the grinding wheel so that the grinding wheel is advanced toward the work an amount to compensate for any material removed therefrom. As 70 is well known, a grinding wheel during use is subjected to wear and if this wear is of a greater amount than the stock removed in one pass of the diamond relative thereto, the wheel will be 75 fed toward the work that amount. If the grind-

ing wheel has a sufficiently true face that it is not necessary to trim same, the grinding continues without further adjustment of the parts. If, however, the wheel face needs truing, the valve on the rail 26 is again actuated for again passing the diamond across the wheel. As it reaches its other end of movement, it will again close the switch 177 for completing the electrical circuits above described.

After the diamond has traversed the wheel in one direction the manual control valve is reversely actuated for withdrawing the diamond to its other end of travel. As it nears said end of travel it is engaged by the stop screw 182 which shifts the rack plunger 147 in a direction opposite to that in which it was shifted by the screw 176 thereby feeding the diamond toward the grinding wheel preparatory to its next traverse relative to the wheel. The reverse movement of the slide 124 also releases the switch actuator 178 so that the spring 217 associated therewith breaks the electrical circuit to the time relay 208 allowing it to de-energize and break the circuit to the solenoid 204. Upon de-energization of the solenoid, 204, the spring 214 which was expanded upon movement of the core 203 reversely shifts the valve 186 to the position shown in Figure 12 thereby retracting the piston 102 preparatory to the next actuation of the diamond relative to the wheel.

Through the adjustment of screws 113 and 154, associated respectively with pawls 109 and 150, the amount of rotation of the ratchets 93 and 140 per oscillation respectively of the segmental gears 99 and 144 may be varied and held equal. In other words, the oscillation of the segmental gears 99 and 144 is through equal arcs and the rotation or actuation of the ratchets must also be equal so the grinding wheel is fed toward the work an amount equal to the reduction of the wheel as determined by the infeed set of the diamond as it passes thereover. This takes place even though the diamond does not actually remove any material from the wheel.

From the foregoing it will be noted that there has been provided a mechanism for maintaining an accurate set up of the wheel and work for producing successive work pieces to the same size within very close limits of tolerance.

What is claimed is:

1. In a mechanism of the class described the combination of a grinding wheel, a work support adjacent the grinding wheel, hydraulically actuatable means for incrementally feeding the wheel toward the work support, means for truing the active face of the wheel, means for actuating the truing tool toward the axis of the wheel, and means operable by the truing mechanism for operating the grinding wheel feeding means to advance the grinding wheel toward the work an amount equal to the feeding of the truing tool toward the wheel.

2. In a grinding machine for producing work pieces within definite limits of tolerance the combination of a bed, a grinding wheel mounted thereon for movement relative thereto, a work support on the bed in the line of movement of the grinding wheel, a truing tool mounted on the bed for movement transversely of the grinding wheel, hydraulic means for actuating the truing tool, means for incrementally feeding the wheel relative to the bed, and means operable by the truing tool for energizing the incremental feeding movement.

3. In a grinding machine for producing work

- pieces within definite limits of tolerance the combination of a bed, a grinding wheel mounted thereon for movement relative thereto, a work support on the bed in the line of movement of the 5 grinding wheel, a truing tool mounted on the bed for movement transversely of the grinding wheel, hydraulic means for actuating the truing tool, means for incrementally feeding the wheel relative to the bed, means operable by the truing 10 tool for energizing the incremental feeding movement, and means for feeding the truing tool toward the wheel at one end of the transverse movement of the truing tool.

4. In a machine tool organization of the class 15 described the combination of a bed, a grinding wheel mounted thereon, a work support carried by the bed, means for feeding the grinding wheel and work support one toward the other, a truing mechanism carried by the bed and including a 20 truing tool for truing the active face of the grinding wheel, means for traversing the truing mechanism relative to the face of the grinding wheel, and electro-hydraulic means energizable by the truing mechanism at one end of its movement 25 relative to the grinding wheel for operating the feeding means.

5. In a machine tool organization of the class 30 described the combination of a bed, a grinding wheel mounted thereon, a work support carried by the bed, means for feeding the grinding wheel and work support one toward the other, a truing mechanism carried by the bed and including a 35 truing tool for truing the active face of the grinding wheel, means for traversing the truing mechanism relative to the face of the grinding wheel, electro-hydraulic means energizable by the truing mechanism at one end of its movement relative to the grinding wheel for operating the feeding means, means at the other end of the movement 40 of the truing mechanism for feeding the tool toward the wheel a predetermined amount, and means for adjusting the feed of the truing tool toward the wheel and the relative feed of the wheel and work support whereby equal incremental feeds of the truing tool and work support 45 and grinding wheel are obtained.

6. In a grinding machine for grinding work pieces within prescribed limits of tolerance the combination of a bed, a work support mounted 50 thereon, a grinding wheel carried by the bed, means for effecting an incremental feed of the work support and grinding wheel one toward the other, a truing mechanism including a truing tool actuatable toward and transversely to the operative 55 face of the grinding wheel, means operable by the transverse movement of the mechanism for actuating the truing tool toward the wheel, and means operable by the truing mechanism for actuating the wheel and work support relative to one another an amount equal to the feed of the 60 tool toward the wheel.

7. In a grinding machine for grinding work pieces within prescribed limits of tolerance the combination of a bed, a work support mounted 65 thereon, a grinding wheel carried by the bed, means for effecting an incremental feed of the work support and grinding wheel one toward the other, a truing mechanism including a truing tool actuatable toward and transversely to the 70 operative face of the grinding wheel, means operable by the transverse movement of the mechanism for actuating the tool toward the wheel, and means operable by the truing mechanism for actuating the wheel and work support relative to 75 one another an amount equal to the feed of the

tool toward the wheel, said feeding means each comprising a screw, a rack movable relative to the screw, and a coupling between the rack and screw operable by the rack when moved in one direction for effecting the feeding.

8. In a grinding machine for grinding work pieces within prescribed limits of tolerance the combination of a bed, a work support mounted thereon, a grinding wheel carried by the bed, means for effecting an incremental feed of the work support and grinding wheel one toward the other, a truing mechanism including a truing tool actuatable toward and transversely to the operative face of the grinding wheel, means operable by the transverse movement of the mechanism for actuating the tool toward the wheel, and means operable by the truing mechanism for actuating the wheel and work support relative to one another an amount equal to the feed of the tool toward the wheel, said feeding means each comprising a screw, a rack movable relative to the screw, a coupling between the rack and screw operable by the rack when moved in one direction for effecting the feeding, and means for resetting the rack.

9. In a mechanism of the class described the combination of a bed, a work support and tool support mounted on the bed for movement one toward and from the other, a feeding mechanism for effecting an intermittent incremental feed thereof, a truing mechanism operable toward and transversely of the grinding wheel and including a truing tool for operation on the wheel, and hydraulically controlled means operable in sequential order for first feeding the truing tool toward and transversely of the grinding wheel and work support relative to one another.

10. In a grinding machine the combination of a bed, a work support and a grinding wheel carried by the bed, feeding means for feeding the grinding wheel and work support one relative to the other a predetermined incremental amount, means transversely shiftable relative to the grinding wheel for truing same, means for feeding the truing means toward the grinding wheel a predetermined incremental amount for each transverse shifting thereof, means for controlling the shifting of the truing mechanism relative to the grinding wheel, means for controlling the wheel and work support feeding means, and means operable by the truing means at the conclusion of its transversing movement for energizing the wheel and work support feed controlling means.

11. In a grinding machine the combination of a bed, a work support and a grinding wheel carried by the bed, feeding means for feeding the grinding wheel and work support relative to one another a predetermined incremental amount, means transversely shiftable relative to the grinding wheel for truing same, means for feeding the truing means toward the grinding wheel a predetermined incremental amount for each transverse shifting thereof, hydraulic means for transversely actuating the truing means relative to the grinding wheel, a valve controlling the operation of the hydraulic means, electro-hydraulic means controlling the feeding means of the wheel and work support, means operable by the truing means for energizing the electro-hydraulic feed control means, and a manually actuatable member for the hydraulic valve.
